UNITED STATES PATENT OFFICE.

ANTOINE BEDELMANN DU PONT, OF CLEVELAND, OHIO.

WATER-HEATER.

1,299,438.

Specification of Letters Patent.

Patented Apr. 8, 1919.

Application filed August 20, 1917. Serial No. 187,057.

To all whom it may concern:

Be it known that I, ANTOINE BEDELMANN DU PONT, citizen of the United States, residing at Cleveland, in the county of Cuyahoga and State of Ohio, have invented certain new and useful Improvements in Water-Heaters, of which the following is a specification.

My invention relates to an improvement in water heaters, in which a plurality of water-circulating elements are connected in a particular way to utilize the outgoing heat products of the heater in pre-heating the cold water coming into the circulating elements and in increasing the temperature of the pre-heated water before delivering the same into a common discharge pipe, and in which each water-circulating element communicates directly with the said main discharge pipe to assure an unrestricted circulation and effect the highest degree of heating results with absolute safety and great economy.

In the accompanying drawing, Figure 1 is a sectional view of a heater containing a pair of water-circulating coils arranged and connected according to my invention, and Figs. 2 and 3 are sectional and side views, respectively, of modified forms of the apparatus, all as hereinafter more particularly described.

Thus, in Fig. 1 I show a cylindrical heater casing 2 having a gas burner 3 beneath its open bottom and equipped with an exhaust pipe 4 at its top. Two separate coils of pipe 5 and 6, respectively, are supported in any suitable way, one above the other centrally with the combustion chamber 7, and the upper coil 5 has a cold water supply pipe 8 connected with its bottom intake end. The flow of water is upwardly through the pipe 5 and in the same general direction as the products of combustion which move upwardly through combustion chamber 7, and the hot water from coil 5 is directly downwardly from its upper end into the bottom of the lower coil 6 by vertical pipe 9. Coil 6 is placed immediately above and in close proximity to burner 3 and is exposed to the greatest heat derived therefrom, while upper burner 5 is mounted in a zone of lower temperature, that is, it is more remote and heated by the out-going products of combustion. Thus, the cold water is first heated by the exhaust heat-products and then subjected to a more intense heat upon displacing the more highly heated water in lower coil 6 which occupies the zone of highest temperature in

combustion chamber 7. Consequently when the water is discharged from the upper end of lower coil 6 into the stand-pipe 10 of the circulating system the water is in a highly-heated state, and obviously any vapor or steam produced during such heating in lower coil 6 is free to escape through stand-pipe 10. Similar relief is obtained for upper coil 5 by a short pipe connection 12 extending from the upper end of said coil 5 to stand-pipe 10, and this communicating pipe or passage is also of utility in effecting constant circulation of the water through the coils under all working conditions. In fact, the apparatus would be unsafe and unreliable without the connecting pipe 12 as this pipe affords relief of vapors and overflow of hot water under high-heating conditions and permits a return flow to coil 5 from stand-pipe 10 whenever a condition arises to cause such return flow. Furthermore, the apparatus may be operated very effectively with a relatively low consumption of fuel.

In Fig. 2, I show three chambered sections 14, 15 and 16 superposed and having vertical tubes 17 in open communication at their ends for the passage of the heat products from a burner 18 located beneath the bottom section, and the upper section has a cover 19 with a central exhaust pipe 20. The cold water is supplied to the bottom end of the uppermost section 14 by way of intake 21 and is discharged from the upper end of said section 14 by a pipe 22 which connects with the middle section 15 near its bottom. This middle section has a discharge pipe 23 at its upper end which extends downward and connects with the lower end of the bottom section 17, and a discharge pipe 24 from the upper end of section 17 connects with a stand-pipe 25. The upper ends of both circulating pipes 22 and 23 have open communication with the stand-pipe by separate connecting pipes 26 and 27, respectively, thereby affording separate relief and circulating passages between the upper end of each section and the stand-pipe.

In Fig. 3 I show a single unit 28 for a hot-water heating furnace having hollow walls divided into two separate chambers 29 and 30 through which the water is caused to circulate as in the other apparatus described. Thus, the upper half of the unit has an intake pipe 31 at one side and lower end thereof, and a discharge pipe 32 centrally at its top which connects with a vertical pipe 33

communicating with the lower part of chamber 30 in the lower half of the unit. This chamber 30 has a discharge pipe 34 at its upper end which connects with stand-pipe 35, and the water flows first through upper chamber 29 and then through the lower chamber 30 and to the stand-pipe on account of the higher temperatures produced in the lower half of the unit at the main seat of combustion above the grate bars 36. A short pipe 37 connects pipe 32 with the stand-pipe 35 for relief of vapors and complete and constant circulation of water under all conditions arising in operations, and to afford absolute safety and the maximum effectiveness and economy in operations.

What I claim is:

A water heater comprising a plurality of

water-circulating units arranged one above the other and a fuel burner at the bottom of said units in heating relations therewith, the said units having open pipe connection running from the top of one unit to the one next beneath for the downward flow of the gradually heated water, a hot water discharge pipe for all said units connected at its lower end with the upper portion of the bottom unit and by branch pipes with the upper portions of the superposed units, and a safety pipe from the top of each of said branch pipes having pipe connection with the said discharge pipe.

Signed at Cleveland, in the county of Cuyahoga, and State of Ohio, this 4th day of May, 1917.

ANTOINE BEDELMANN DU PONT.
